COMBINATION TAPE AND ADHESIVE APPLICA-
TOR FOR BINDING CARPETS OR THE LIKE

Charles R. Brown, 120 Jericho Road, Battle Creek, Mich.

Filed Oct. 28, 1959, Ser. No. 58,095

Term of patent 14 years

(Cl. D74—1)

Fig. 1.

Fig. 2.

Fig. 3.

Fig. 4.

The side of the apparatus opposite to that shown in Figure 2 is substantially plain.

I claim:

The ornamental design for a combination tape and adhesive applicator for binding carpets or the like, substantially as shown and described.
